UNITED STATES PATENT OFFICE

PAUL SANDER, OF CHEMNITZ, GERMANY

ENDLESS PATTERN BAND FOR TEXTILE MACHINERY

Application filed October 13, 1927, Serial No. 225,950, and in Germany June 18, 1927.

My invention relates to textile machinery and more especially to patterning mechanism adapted for use more especially in connection with circular knitting machines. It has particular reference to an endless pattern band which is arranged in a new and advantageous manner, which enables long endless bands to be accommodated in the machine and to be supported therein in a more efficient manner than was hitherto possible.

10 An embodiment of the invention is illustrated, by way of example, in the accompanying drawing, in which

15 Fig. 1 shows the pattern band in a perspective view.

Fig. 2 shows the sprocket wheel with the pattern band and with a portion of the knitting machine viewed from the side, the machine being shown in section.

20 Fig. 3 is a top plan view of the parts shown in Fig. 2, partly in section.

That portion 2 of the endless pattern band 1 which is inoperative for the time being, is wound into a flat spiral like a clock-spring, which is held on all sides between rollers 3. The operative portion of the pattern-band starts from the inner side of the spiral, passing around a drum or wheel 4 and then over a sprocket wheel 5 to return 25 to the spiral from the outer side. At a suitable point such as α the band acts by means of slots 6 or other perforations provided therein upon the heels of the needles or jacks of the knitting-machine, but it may also be substituted in other machines for the jac- 30 quard apparatus. A spur-wheel 7 serves to rotate the sprocket wheel 5 the teeth 8 of which convey the pattern-band 1 by en-gaging in holes 9 near the upper edge of band 1.

In order to prevent those portions of the band, which are not perforated, from being deformed in contact with the heels of the jacks, the sprocket wheel has projecting ribs 45 10 formed on its rim between radial indentations, the solid portions 12 of the pattern band between these slots being supported by these ribs. The indentations 15 are spaced in accordance with the spacing of the 50 jacks 11. The ribs 10 thus supporting the

solid portions 12 of the pattern band these solid portions cannot bend under the pressure exerted upon them by the heels of the jacks. The heels 13 of these jacks which remain at rest are, therefore, properly pushed 55 back, the heels of the other jacks passing freely through the slots 6 in the pattern band 1.

I wish it to be understood that I do not desire to be limited to the exact details of 60 construction shown and described for obvious modifications will occur to a person skilled in the art.

I claim:—

1. A knitting machine comprising a needle 65 bed arranged to describe a circle, an endless apertured pattern band, means for supporting the operative portion of said band, means for transporting said band to operative pattern selecting position, the inoperative portion of said band being wound into a flat spiral, the operative portion extending from the inner and outer part of the spiral as a continuous band around said transporting means and to pattern selecting 70 position and means for driving said transporting means in synchronism with said needle bed to transport said pattern band from said spiral to the operative position of pattern selection and back to inoperative 75 position in the spiral. 80

2. A knitting machine comprising a needle bed arranged to describe a circle, an endless apertured pattern band, means for supporting the operative portion of said band, a sprocket wheel for transporting said band to operative pattern selecting position, the inoperative portion of said band being wound into a flat spiral, the operative portion 85 extending from the inner and outer part of the spiral as a continuous band around said transporting wheel and to pattern selecting position and means for driving said transporting wheel in synchronism 90 with said needle bed to transport said pattern band from said spiral to the operative position of pattern selection and back to inoperative position in the spiral, said 95 sprocket wheel being formed on its circum- 100

ference with indentations registering with the apertures of said band, ribs formed between adjoining indentations acting as supports for the nonapertured portions of said band.

5 In testimony whereof I affix my signature.

PAUL SANDER.
